UNITED STATES PATENT OFFICE.

FRANK L. SESSIONS, OF COLUMBUS, OHIO, ASSIGNOR TO THE JEFFREY MANUFACTURING COMPANY, A CORPORATION OF OHIO.

WINDING MECHANISM.

1,137,237.

Specification of Letters Patent. Patented Apr. 27, 1915.

Original application filed September 12, 1907, Serial No. 392,577. Divided and this application filed October 19, 1910. Serial No. 587,975.

To all whom it may concern:

Be it known that I, FRANK L. SESSIONS, a citizen of the United States, residing at Columbus, in the county of Franklin and State of Ohio, have invented certain new and useful Improvements in Winding Mechanisms, of which the following is a specification, reference being had therein to the accompanying drawing.

10 This invention relates to improvements in winding mechanisms, of a kind particularly adapted for use on electric mine locomotives.

In coal mines, operated on the room and pillar plan, it is the practice to mine the coal at each of numerous points. After the masses are loosened the cars are distributed, one being taken to each of the places of mining. After they are loaded they are brought 20 individually from the rooms to the place where they are coupled into trains or "trips". Electrically driven locomotives are now largely employed for this "gathering" purpose. The rooms and branch mine 25 passageways leading to the rooms of a mine are, as a usual rule, not equipped with a trolley wire or other extended stationary conductor for supplying current to the locomotives. The tracks in these branch passageways and rooms where the coal is cut 30 and loaded, are temporary in character, and it is uneconomical to provide trolley wire equipment over these temporary tracks. The main passages of the mines are equipped 35 with trolley wires. When the locomotives leave these main entries to enter the rooms, current must be supplied them by some means other than running contact of the trolley wheel with the trolley wire. One 40 of the means quite generally employed for this purpose, is a flexible conductor cable which is wound upon a reel carried by the locomotive and is attachable at its free end to a trolley wire at the point where the locomotive leaves the trolley-equipped entry.

The object of this invention is to provide such a reel of an improved type and with an improved drive mechanism for operating it.

50 As it is impossible to gain a clear conception of my invention without an understanding of the manner in which it is used and of the mechanism with which it is associated, I will show in the drawings and de-

scribe rather fully an electric locomotive of 55 the type upon which a winding mechanism of my invention is adapted to be used, and will show and describe the winding mechanism in position thereupon.

Figure 1 is a top plan view of a locomotive 60 equipped with a winding mechanism embodying my invention. Fig. 2 is a side elevation of the same. Fig. 3 is an end elevation of the winding devices and the frame parts supporting them, the side parts of the 65 locomotive being shown in vertical section. Fig. 4 is a longitudinal sectional view of the winding devices and associated locomotive parts. Fig. 5 is a fragmentary detail view of a part of the controlling device for one 70 of the clutches.

The locomotive shown is formed with cast iron side frame elements 1 and 2. These are preferably cast integral from end to end. At their ends they are connected to cross 75 frame pieces 3, 4, each of these also being integral from side to side. Each of the side pieces is formed with two rectangular openings and in each opening there is fitted the journal box or bearing for receiving the end 80 of an axle. The axles are indicated respectively by 6 and 7. In the space between the axles there is mounted an electric motor 8 to which current is usually supplied by trolley mechanism indicated by 9 this being 85 of any suitable character. Just inside of the end cross piece 3 of the frame there is a chamber or space within which are located the parts by which the motorman is enabled to control the car and manipulate various 90 parts carried thereby.

10 indicates an electric controller which is preferably in circuit between the trolley mechanism and the motor.

A wheel brake system is shown, but as 95 this is not within the scope of the invention to which the present application relates, it is unnecessary to describe it in detail. The brake mechanism is operated by a hand wheel and screw at 12 which are mounted in 100 a cross bearing bar 12a.

The electric motor is connected to one of the axles by gearing and this axle is connected by a sprocket 13 and a chain with a sprocket wheel 14 on the other axle, so that 105 power is transmitted to both. The armature shaft of the motor is by means of the coupling at 51 coupled to a shaft 46 which carries

the worm 45. This worm engages with a worm wheel 15 on the axle 6. On the hub of the worm wheel 15 there are clutch teeth 21 with which engage the teeth on an opposing clutch element 22. The latter is connected to the axle 6 by a feather or spline and can be moved into or out of engagement with the clutch element at 21 by means of the shifting devices comprising fork 23, a 5 rock shaft 24 and a hand lever 25 near the motorman, the shaft 24 being mounted in the bracket bearings at 26, 27.

The worm 45 above referred to is mounted on the shaft 46 and has thrust collars 47 and 10 48, one on each side, provided with ball bearings. The worm shaft 46 is supported in bearings 49 and 50 on the upper part of the gear case 30. The pitch of the thread of the worm 45 and of the teeth on the worm 15 wheel 15 is such that the worm wheel will 20 drive the worm when the locomotive is coasting or drifting, as for example, when the current is cut out of the motor and the car is still advancing and its axle rotating.

25 The reeling mechanism is carried by a frame indicated at 57, 58 and 59. This frame is supported by bars 55, 56, which are secured to the side parts 1 and 2 of the car body frame extending across from one to 30 the other. The upper part of the frame 57 has flanges at the bottom to which are bolted the lower part of the frame, the castings 58 and 59. Mounted in this frame is a vertical shaft 60 carrying a worm wheel 61, and these 35 are driven by the worm 62 on the shaft 63. This shaft receives power from the sprocket wheel 66 on the end of the above mentioned worm shaft 46, through a chain 65 connected to a sprocket wheel 64 on the worm shaft 63.

40 The casting 58 above referred to and a supplemental casting 67 are so formed and secured together as to inclose the worm 62 and the worm wheel 61, and moreover they are formed with bearings for the shaft 63. 45 The said castings 58 and 67 have vertically extending bosses or hubs 68 and 69 which furnish bearings for the vertical shaft 60. The frame casting 57 is extended upward to a horizontal plane sufficiently high and is 50 formed with a reel support 57^a shaped to provide part of a ball race 70. In this are placed a suitable number of steel balls 71.

55 And on these a holder in the form of a cast iron ring 72 is arranged to rest, this having a circular groove to form the upper element of the ball race. The upper surface of this holder or ring 72 is flat as shown at 73, but its outer edge is provided with square teeth as at 74, to provide a ratchet.

60 76 is a pawl pivoted to the stud 75 which is secured to the upper part of the frame piece or casting 57, this pawl being adapted to engage the ratchet teeth at 74. 77 is a counterweight also pivoted to the stud 75 65 and connected to the pawl 76 by the bolt

78. The pawl has two active ends, one projecting to the right from the pivot 75 and the other to the left. It has also two points of attachment for the bolt 78 to the weight 77. By transferring the weight and bolt 70 from one side to the other of the center the direction of action of the pawl can be reversed.

79 indicates the cable reel, preferably formed in the way shown and resting upon the flat surface 73 of the holder 72 and adapted to revolve with the ring on the anti-friction balls at 71. When, however, the ring or holder 72 is prevented from revolving by the pawl and ratchet, the reel can be 75 revolved only by sliding or slipping on the face 73, which forms a brake to prevent the cable from being unwound more freely than is desired at times. At the axis of the reel there is a shaft 83 in line with but separated from the aforesaid lower shaft 60. The upper shaft 83 is mounted in and projects upwardly from the top of the frame part or casting 57. Between this shaft and the reel there is interposed a friction clutch. 80 One member of this is a plate or flange 80 projecting inwardly from the periphery part of the reel. The other member is composed of two plates or flanges 81 and 82 keyed to the shaft 83, these overlapping a 85 central annular part of the flange or plate 80, one lying above, the other lying below it. Frictional engagement under pressure is produced by means of a spring 83^a and the adjustable nuts 83^b both above the clutch plate 82, the spring acting to clamp the plates 81 and 82 against the horizontal surfaces of the flange or plate 80. The shaft 83 is shouldered just below the plate 81 to prevent the spring 83^a from causing any relative movement of plate 81 and the shaft. 90

84 indicates the bearing for the shaft 83, it being central with the ball race 70 and serving to retain the reel and the clutches in proper position. There is sufficient clearance to allow the entire shaft 83 and the clutch plates, to rest under their weight on the ring 72 and the balls 71. Shaft 83 projects below bearing 84 and upon it there is slidably mounted a righthand spiral jaw clutch 85 normally tending to drop downward a certain distance under its weight. 95 86 is a shifting form which engages with this and carries the weight of this clutch member. The fork is secured to the rock shaft 87 which is mounted in bracket bearings 88-89 formed on or secured to the stationary frame or casting 57.

90 is a rocker arm or crank secured to the shaft 87, and 91 is a shifting rod connected to this rocker arm and extending to the motorman's end of the locomotive. At its rear end this rod 91 rests on a cross bar 12^a and is held against it by the tension spring 91^a. It is enlarged to form a latch 91^b so 100

shaped that when the clutch 85 is in contact with the opposing clutch-element 93, this latch will rest on top of the cross bar 12^a, but as the rod is drawn backward the bevel face of the latch will be forced downward and backward by the spring 91^a and the clutch member 85 will be lifted to the frame casting 57.

The shaft 60, above described, carries at its upper end a right-hand spiral jaw clutch member 92. Between this and the aforesaid clutch member 85 there is interposed a clutch ring 93 having two sets of clutch teeth, a set of right-hand teeth on its upper face and a set of left-hand teeth on its lower face. It may be clamped to either of the parts 85 and 92 by clamping ring 94 having inwardly projecting flanges which correspond to suitable grooves in the three clutch members. By means of this clamping ring the clutch can be readily converted from right-hand to left-hand or from left to right as may be desired.

The flange 80, of the reel 79, also serves as a support for the ring of insulation at 95 to which is secured the collector ring 96. The electric cable (for the winding of which the reel is employed) has the inner end of its conductor electrically connected to this collector ring 96, the end part of the cable being passed through the aperture in the reel periphery at 96^a and a binding lug 97 being provided for firmly fastening the end of the metallic conductor. From the collector ring 96, the current is taken to a stationary circuit terminal at 100 by means of the contact finger 99, carried by the insulating block 98 and supported upon the stationary frame casting 57 in such way as to press against the collector ring. The cable can be taken to and from the reel as it is being wound or unwound from points along the track either in front of or behind the locomotive. At each end of the locomotive there are mounted upon the side frames 1 and 2 suitable guide rollers 1^a and 2^a to properly direct the cable as it is being taken up or paid out.

The devices above described are for the purpose of conducting current to the electric apparatus on the car when the trolley mechanism is out of operation. For instance, when isolated cars are to be taken out of the mine rooms after they have been loaded and gathered on the tracks in the entries for making up trains, and when these cars are at a distance from the main current-supplying wires the cable is availed of for actuating the motors on the locomotives.

The operation of the electric cable reel is as follows: The cable having been wound on the reel in the proper direction, it is desired to take the locomotive into a room where there is no trolley wire. The free end of the cable is connected with the trolley wire by appropriate attachments, and the trolley

is locked in such a position as to be out of the way. The motor now receives current through the cable and the collector mechanism on the reel, and may be run into the room, the cable unwinding as the locomotive 70 proceeds. As the pawl 76, engaging the ratchet 74, prevents the revolution of the brake ring 72, the reel 79 will slide on the face 73 of the brake ring 72, the retarding effect of which will prevent too rapid unwinding of the cable, and tend to hold it off the ground. Before starting to return, the operator pushes the rod 91 forward until the latch 91^b rests on top of the cross bar 12^a. This will cause the clutch 85 to engage with 80 the clutch 93, and, when the locomotive starts, the friction disks 81 and 82 will cause the reel to revolve in the winding direction. As the pawl 76 does not prevent the ring 72 from revolving in this direction, the whole 85 device revolves on the ball bearings 71 without unnecessary friction. The proportions of the reel and its driving members are such that the tendency is for the reel to revolve faster than the cable will wind. This is compensated for by the slipping of the friction clutch members 81 and 82 against the flange 80, the pressure of the spring 83^a being so adjusted as to keep a desirable tension on the cable. When the locomotive reaches the 90 entry, and the cable is disconnected from the trolley wire, the clutch 85 should be thrown out to prevent unnecessary wear on the friction members 80, 81 and 82; but, if the direction of the locomotive is reversed, the clutch 100 member 85 will climb on the face of the clutch member 93, thus rocking the arm 90, which will push the rod 91 forward until the latch 91^b slips over the edge of the cross bar 12^a, and the spring 91^a will force the rod 105 clear back and insure the clutch 85 clearing the teeth on 93.

If for any reason it is desired to use the locomotive in a part of the mine where it will be necessary to enter the rooms rear end first, the clamping ring 94 may be shifted to clamp the ring 93 to the clutch 85, making a left-hand clutch instead of a righthand; the counterweight 77 shifted to the other side of the pawl 76; and the cable entirely unwound and rewound in the opposite direction; after which the operation is as before. 110 115

While I have herein shown the winding mechanism upon an electric locomotive and used to reel a conductor cable which supplies current to the motors of the locomotive, I do not wish to be understood as restricting my invention to this particular application, as winding mechanisms of the kind herein set forth and described in the following claims are capable of a variety of uses other than the one exemplified in the drawings and description. 120 125

I do not herein claim the combination of the winding reel with the locomotive, nor 180

any novel features shown and described in connection with the locomotive, its driving gearing, etc., other than the winding mechanism which has been above described, these 5 matters having been already claimed in my application, Serial No. 392,577, filed September 12, 1907, of which this application is a division.

What I claim is:

- 10 1. In a winding mechanism, the combination of a reel adapted for winding and unwinding a cable, reversible drive shafting, and a single direction drive clutch mechanism adjustable to either drive the reel in one direction only of rotation or to drive the reel in the other direction only of rotation, the clutch mechanism in one position of adjustment automatically connecting the drive shafting and the reel when the drive shafting is rotating in a given direction and disconnecting the drive shafting and the reel when the drive shafting is rotating in the opposite direction, and the clutch mechanism in the other position of adjustment 20 automatically connecting the drive shafting and the reel when the drive shafting is rotating in the said opposite direction and disconnecting the shafting and reel when the shafting is rotating in the said given direction.
- 25 2. In a winding mechanism, the combination of a reel mounted for rotation about a vertical axis, a holder having a friction surface upon which the reel rests slidably, a bearing upon which the holder rotates, a driving mechanism for the reel connected thereto independently of the holder, and means for preventing the rotation of the holder in one direction while freely permitting rotation in the other.
- 30 3. In a winding mechanism, the combination of a reel mounted for rotation about a vertical axis, a holder having a friction surface upon which the reel rests slidably, a bearing upon which the holder rotates, a driver for the reel, a friction clutch supplemental to the said holder interposed between the driver and the reel, and means for preventing the rotation of the holder in one direction while permitting it to freely rotate in the other.
- 35 4. In a winding mechanism, the combination of a reel mounted on a vertical axis, a holder having a friction surface upon which the reel rests slidably, a bearing upon which the holder rotates, a driver for the reel, a friction clutch interposed between the driver and the reel and having its clutching parts adjustable to vary their engaging pressure, and means for preventing the rotating of the holder in one direction.
- 40 5. In a winding mechanism, the combination of a reel mounted for rotation about a vertical axis, a holder for the reel having frictional engagement therewith, an anti-

friction bearing upon which the holder rests, and means for preventing the rotation of the holder in one direction or for preventing the rotation of the holder in the other direction as desired.

70

6. In a winding mechanism, the combination of a reel mounted on a vertical axis, a drive shaft, power devices for rotating the shaft, a friction clutch between the drive shaft and the reel, a stationary support, a ratcheted rotatably holder on which the reel slidably rests, a pawl for the holder, and a positive clutch between the drive shaft and the power devices.

75

7. The combination of a reel adapted for winding and unwinding, a cable, a reversible shaft for driving the reel, a three-part clutch between the shaft and reel adapted to have the second part detachably connected with the first part for rotating the reel in one direction only and detachably connected with the third part for rotating the reel in the opposite direction only.

80

8. In a winding mechanism, the combination of a reel adapted for winding and unwinding a cable, a shaft connected to the reel, a reversible drive shaft alining therewith, and a clutch mechanism between the two shafts adjustable to two positions, the mechanism in one position being capable of imparting rotation in one direction only to the reel shaft and only when the drive shaft is rotating in a given direction only, and when in the other position of adjustment being capable of imparting rotation to the reel shaft in the other direction and only when the drive shaft is rotating in the other direction.

85

9. In a winding mechanism, the combination of a reel adapted for winding and unwinding a cable, power mechanism for operating the reel, and a single-direction-drive positive clutch mechanism adjustable to reverse the single direction in which it will operate, the clutch mechanism being operatively interposed between the power mechanism and the reel.

90

10. In a winding mechanism, the combination of a reel adapted for winding and unwinding a cable, power mechanism for operating the reel, a reversible pawl-and-ratchet mechanism connected with the reel for preventing rotation of the reel in one direction or in the other direction as may be desired, and a reversible single-direction-drive positive clutch mechanism interposed between the reel and the power mechanism.

105

11. In a winding mechanism, the combination of a reel mounted for rotation about a vertical axis, a stationary support, a ratcheted reel holder interposed between the support and the reel, an anti-friction bearing between the holder and the support, and a reversible pawl device for engaging the holder to prevent rotation of the holder.

110

115

120

125

130

in one direction, or in the other direction as may be desired.

12. In a winding mechanism, the combination of a reel mounted for rotation about a vertical axis, a reel holder having slideable frictional engagement with the reel, an anti-friction bearing for the holder, a device for preventing rotation of the holder in one direction or in the other as may be desired, and a reel driving means comprising a friction clutch the parts of which are adjustable to vary their engaging pressure.

13. In a winding mechanism, the combination of a reel mounted for rotation about a vertical axis, a rotatable holder which supports the reel and has frictional engagement therewith, a device for preventing rotation of the holder in one direction or in the other as may be desired, and a reel driving means comprising a friction clutch.

14. In a winding mechanism, the combination of a reel mounted for rotation about a vertical axis, a rotatable holder which supports the reel and has slideable engagement with it, a device for holding the reel against rotation in one direction, or in the other as may be desired, and a drive mechanism for the reel comprising a friction clutch and a manually controllable positive clutch.

15. In a winding mechanism, the combination of a reel, a reversible power shaft, a reel driving clutch between the shaft and the reel capable of transmitting power in one direction only or in the other direction only as may be desired, and a manually controllable means for disengaging the clutch elements to break the power connection.

16. In a winding mechanism, the combination of a rotatable reel, a reversible power shaft, and power transmitting means between the shaft and the reel, comprising a friction clutch and a clutch capable of transmitting power in one direction only or in the other direction only as may be desired.

17. In a winding mechanism, the combination of a rotatable reel, a reel driving shaft, a friction clutch interposed between the shaft and the reel, a reversible power shaft, and a clutch between the two shafts capable of transmitting power in one direction only or in the other direction only as may be desired.

18. In a winding mechanism, the combination of a reel rotatable about a vertical axis, a rotatable holder which supports the reel and frictionally engages with it, a reversible pawl device for engaging the holder to prevent its rotation in one direction or for preventing its rotation in the other direction as desired, and a clutch capable of

transmitting power to rotate the reel in one direction only or in the other direction only as may be desired.

65

19. In a winding mechanism, the combination of a reel, an element frictionally engaging the reel and rotatable concentrically therewith, a reversible pawl device for locking the said element against rotation in one direction or the other as may be desired, and a clutch for transmitting power to rotate the reel in one direction only or in the other direction only as may be desired.

20. In a winding mechanism, the combination of a rotatable reel, a reversible means for resisting the rotation of the reel in one direction or in the other as may be desired, and a power transmission system for the reel comprising a friction clutch and a positive clutch capable of transmitting power in one direction only or in the other direction only as may be desired.

75

21. In a winding mechanism, the combination of a reel rotatable about a vertical axis, a rotatable holder which supports the reel, and frictionally engages it, a pawl device for locking the holder against rotation in one direction or in the other as may be desired, and a power transmission system for the reel comprising a friction clutch and a positive clutch capable of transmitting power in one direction only or in the other direction only as may be desired.

85

22. In a winding mechanism, the combination of a reel, an element frictionally engaging the reel and rotatable concentrically with it, a pawl device for locking the said element against rotation in one direction or in the other as may be desired, and a power transmission system for the reel comprising a friction clutch and a positive clutch capable of transmitting power in one direction only or in the other direction only as may be desired.

95

23. In a cable winding mechanism, the combination of a rotatable reel, a flexible cable connected with the reel and adapted to be wound thereon in either direction, a manually reversible motor, and a power mechanism between the motor and the reel comprising a clutch capable of transmitting power in one direction only or in the other direction only, whereby, for either direction of winding of the cable on the reel, the parts may be adjusted to transmit power from the motor to the reel only in the cable winding direction.
